UNITED STATES PATENT OFFICE

115,120

DESIGN FOR A STEREOCAMPIMETER

John R. Miles, Rochester, N. Y., assignor to
Bausch & Lomb Optical Company, Rochester,
N. Y., a corporation of New York

Application February 16, 1939, Serial No. 83,013

Term of patent 7 years

To all whom it may concern:

Be it known that I, John R. Miles, a citizen of the United States and a resident of Rochester, county of Monroe, and State of New York, have invented a new, original, and ornamental Design for a Stereocampimeter, of which the following is a specification, reference being had to the accompanying drawing, forming a part thereof.

Fig. 1 is a front perspective view of a stereocampimeter embodying my new design.

Fig. 2 is a side perspective view thereof.

I claim:

The ornamental design for a stereocampimeter, substantially as shown.

JOHN R. MILES.
